UNITED STATES PATENT OFFICE.

JOHN H. ZOLDOWSKI, OF TOLEDO, OHIO, ASSIGNOR OF ONE-TENTH TO FRANK CHAPP,
OF TOLEDO, OHIO.

WINDOW LIFTER.

Application filed October 26, 1921. Serial No. 508,926.

To all whom it may concern:

Be it known that I, JOHN H. ZOLDOWSKI, a citizen of the United States, and a resident of Toledo, in the county of Lucas and State 5 of Ohio, have made an Invention Appertaining to Window Lifters; and I do hereby declare the following to be a full, clear, and exact description of the invention, such as will enable others skilled in the art to which

10 it appertains to make and use the same, reference being had to the accompanying drawings, and to the characters of reference marked thereon, which form a part of this specification.

15 My invention has for its object to provide an efficient and simple means for lifting frames, such as windows. It particularly has for its object to provide a simple means for lifting the windows of an automobile, either in the door or in other parts 20 of a coupé or limousine or other closed automobile body.

The invention may be contained in structures that partake of different forms in their 25 details, and to illustrate a practical application of the invention I have selected a structure containing the invention as an example of such structures and shall describe it hereinafter. The structure selected is 30 illustrated in the accompanying drawings.

Figure 1 is a side broken view showing the means for raising the window illustrated in the figure. Fig. 2 is a sectional view taken on the line 2-2 indicated in Fig. 1. Fig. 3 is a sectional view taken on the line 3-3 also indicated in Fig. 1. Fig. 4 is a side view of a supporting plate.

1, in Fig. 1, is a frame of a part of an automobile. In the particular instance selected it is the frame of a door of a closed body of an automobile. 2 is the glass plate which may be located in a frame 3 forming a window frame. As is well known in the art the part marked 3 may be nothing more 45 than a U-shaped strip covering the lower edge of the window.

A pair of rollers 4 supported on the ends of arms 5 and 6 is raised to press its roller against the frame 3 by means of the spring 7 which is pivoted in the bracket 8 and may

be secured to the frame 1. The arm 6 is provided with a plurality of notches 9 in which the turned end of the spring 7 may be inserted to adjust the pressure of the roller 4 of the arm 6 against the frame. A 55 part of the weight of the window 2 is thus counter-balanced by the action of the spring 7. The arm 5 is pivotally supported in the plate 10 which is secured to a part of the frame or to the door. The lower end of 60 the arm is provided with teeth that mesh with the pinion or sector 11 which is also pivoted in the plate 10 by means of the pivot pin 12. The pin 12 is connected to the arm 13 which may be provided with the 65 handle 14 for the purpose of rotating the pin 12 and consequently rotating the pinion or rack 11 to raise and lower the arm 5. The face of the plate 10 is provided with a plurality of circular indentations 15 located 70 around the opening 16 through which the pivot pin 12 extends. The hub of the arm 13 is provided with a socket 17 in which is located a ball 18 that is spring-pressed by the spring 19. The socket 17 is located with 75 respect to the axis of the arm so that it will register with the indentations 15. This provides means for releasably connecting the arm 13 in adjusted positions relative to the plate 10 since the ball 18 will enter the indentations 15 and be yieldingly held therein by the operation of the spring 19. When it is desired to raise or lower the window the arm 13 is turned in one direction or the other and the arm 5 will raise or permit the 80 window to be lowered, the spring 7 being adjustably connected with the arm 6 so that the weight of the window will cause it to descend if the arm 5 is lowered.

If desired a rectangular bracket 20 may 85 be secured to the frame 3 and the roller 4 connected to the arm 5 may be inserted in the bracket to positively lower as well as raise the window. The spring 7 may then be adjusted so as to substantially counter- 90 balance the weight of the window.

I claim:

In a window lifting means, a frame, an arm pivotally supported on one side of the frame and extending transversely there- 100

through, a roller located on one end of the said arm for supporting the sash of the window and movable over the lower edge of the sash, the said arm having a circular rack integral with and located at the other end thereof, a pinion meshing with the rack for positively raising and lowering the sash, a plate secured to the frame and hav-

ing recesses located therein, a crank handle connected to the pinion and having a spring 10 pressed ball for engaging in the recesses of the plate for securing the window in any position that it may be raised.

In testimony whereof, I have hereunto signed my name to this specification.

JOHN H. ZOLDOWSKI.
